DEFLECTOR TROUGH FOR SWITCH HEATERS

William P. Scholz, Morristown, N. J.

Application July 17, 1930. Serial No. 468,547

1 Claim. (Cl. 246—428)

The device, the subject of this invention, is intended as a means for supporting a heater, and refers particularly to the type of heater sometimes called a snow melter or switch heater, and used on railroads to melt snow or ice, that might otherwise form or collect in switches, and by its presence, prevent the ready operation of the switch tongue.

In many instances, these heaters are placed in a recess or groove, which has been provided in the rail tie, and under the switch plate.

When heaters are placed in the ties, or closely adjacent thereto, the ties become charred and burnt, and consequently, weakened, and it is for 15 the purpose of overcoming the burning of the tie, or the possibility of setting fire thereto, that I have invented the device which I will now describe, having reference to the drawing which accompanies this application, and which should 20 be considered for a complete understanding of the specification which follows.

In the drawing:—

Fig. 1 shows a tie in section, with a heater, and my device in place therein.

25 Fig. 2 is a side elevation of my device.

Fig. 3 is a top plan view thereof, and

Fig. 4 shows a fractured modification.

Figures 2, 3 and 4 are on a larger scale. Similar reference numerals indicate like parts in all 30 the figures where they appear.

At 1, I show a switch heater. The particular construction of this device will be found fully set forth in a patent application Ser. No. 468,546 made by me, and filed even date herewith. The 35 cross tie is shown at 2, and is provided with a recess 3, into which the heater is inserted. The usual switch plate, which lies on the upper side of the tie and across the heater is omitted.

If the heater were inserted directly into the 40 tie, the tie might become charred or burnt, or a fire might be started, and as the effective heating is to take place only on the switch plate, which is above the heater, I prefer to place around my heater, a deflector which will also 45 serve as a means for preventing the overheating or charring of the tie.

My device is formed as a trough, having a bottom plate 4, and side plates 5 and 6. These plates 50 may be formed integral, one with the other, and the material that I will select for my device should be a heat reflecting material. I may use aluminum or any other desired material.

The members 4, 5 and 6 are formed to produce an open-ended trough, as shown in Fig. 3. 55 It is desirable to separate the trough from the

tie 2, and to maintain it separated, so as to provide an air space such as shown at 7, 8 and 9 on all sides of the trough where it is adjacent to the tie, and to provide and maintain this space, I secure in the bottom and sides of my trough 60 member, projecting plugs.

The plugs 10 and 11 project from the side member 5, and the plugs 12 and 14 project from the side member 6. While the plugs 15, 16, 17 and 18 project from the bottom, and as shown 65 in Figs. 2 and 3, these plugs may be riveted into their respective plates.

As previously stated, the heater 1 is arranged in the trough member, but spaced therefrom. As it is my desire to provide an air space around 70 the heater, or between the heater and the trough, as well as between the trough and the tie, and to maintain the air space between the heater and the trough, I provide additional plugs such as are shown at 19, 20 and 21, secured in the plate 5, 75 and 22, 23 and 24, secured in the plate 6, and I also provide inwardly projecting plugs 25 and 26, secured in the bottom member 4, and upon which the heater member rests.

It will of course be understood that these plugs, 80 which serve as spacing members, are constructed as rivets, and that perforations are provided in each of the plates to receive the smaller diameter of the plug, as suggested at 27 in Fig. 3, and thereafter the short end of the plug is riveted 85 over.

It will be understood that the arrangement of these spacing members may be changed at will, and that all proportions of my device may be changed to meet special requirements. 90

To obtain greatest efficiency, I will probably paint the recess in the tie with aluminum paint, so as to reflect all of the heat.

Having carefully and fully described my invention, what I claim and desire to secure by 95 Letters Patent is:—

In a device of the character described, the combination with a tie having a recess therein, of an open topped trough member arranged therein, spacers secured to said trough to retain said 100 trough away from said tie and a heater member arranged in said trough member and spacers secured to the walls of said trough and being adapted to maintain a clear air space between said heater and said trough. 105

WILLIAM P. SCHOLZ.
